UNITED STATES PATENT OFFICE

ARTHUR W. NELSON, OF PARK RIDGE, ILLINOIS, ASSIGNOR TO LOCOMOTIVE FIREBOX COMPANY, OF CHICAGO, ILLINOIS, A CORPORATION OF DELAWARE

LOCOMOTIVE BOILER

Application filed June 18, 1928. Serial No. 286,443.

This invention relates to improvements in locomotive boilers having a firebox wherein fuel, such as oil is burned in suspension and it consists of the matters hereinafter described and more particularly pointed out in the appended claims.

One of the objects of the invention is to provide an arrangement of certain water heating and circulating elements in the firebox, which partially bottoms the same and includes two downwardly and inwardly extending flat tubular water walls, each of which has enlarged tubular side margins or bulges with the lower or inner side margin of each wall connected by a conduit extending forwardly to the boiler barrel and with the rear end of each outer margin connected to an adjacent side water leg near the back water leg.

Another object of the invention is to provide in a locomotive boiler, a construction of this kind wherein connection with each side water leg may be provided through substantially small openings whereby the parts may be readily removed for converting the firebox into a coal burner as is sometimes necessary.

These objects of the invention, as well as others, together with the many advantages thereof, will more fully appear as I proceed with my specification.

In the drawings:—

Fig. 1 is a longitudinal vertical sectional view through the firebox end of a locomotive boiler embodying my invention.

Fig. 2 is a horizontal sectional view through the same as taken on the line 2—2 of Fig. 1, with the firebrick burner and associated parts omitted to better disclose the construction and arrangement of the water heating and circulating elements.

Fig. 3 is a transverse vertical sectional view through the firebox end of the boiler as taken on the line 3—3 of Fig. 1.

Fig. 4 is another transverse vertical sectional view through the bottom end portion of the firebox as taken on the line 4—4 of Fig. 1.

Referring now in detail to that embodiment of the invention illustrated in the ac-

companying drawings: 1 indicates as a whole the barrel of the boiler in which are arranged the usual flues 2. The firebox of the boiler is formed by the flue sheet 3, rear sheet 4, side sheets 5—5 and crown sheet 6 all connected together in the manner well known. The bottom portion 3^a of the flue sheet forms the throat sheet of the firebox.

The firebox wrapper comprises the top plate 7, the side plates 8—8, the outside throat plate 9 and the outside back plate 10. The wrapper just described, together with the firebox sheets before mentioned, define the several water legs of the boiler i. e., the side legs 11, the front leg or throat 12, and back leg 13 all closed at the bottom by the usual mud ring 14. The firebox sheets are joined to the wrapper plates by means of stay bolts 15 in the manner well known. 16 indicates a door opening which is normally closed by a door (not shown). This opening provides the fuel door opening in case the firebox is converted into a coal burner as is sometimes necessary and which conversion may be readily made with but comparatively small expense.

In the middle bottom portion of the firebox I provide a novel water steaming and circulating means indicated as a whole by the numeral 17 in Fig. 2. Said means comprises a pair of laterally spaced flat, hollow elements or walls 18—18 which are disposed, one along the bottom portion of each side water leg of the boiler and said legs extend downwardly and inwardly therefrom so as to be spaced apart equally on each side of the median line of the firebox. Each element is in the form of a flat tube or body of a length greater than its width and of a suitable depth and so that said element may withstand interior pressures, it is stay-bolted as at 19.

Along the top and bottom side of each element the same is enlarged in diameter to form bulged portions 20 and 21 respectively. Each bulged top portion is extended rearwardly of the flat tubular body 18 to form a short neck 22 and each bulged bottom portion is extended forwardly of the flat tubular body to form a longer neck or intake 23. Preferably each bulged portion is staybolted and the intake

neck 23 is radially flanged for detachable connection with associated conduits as will later appear. To support these elements in position, I affix to the firebox side sheets, shortly above the mud ring, angle bars 24 upon which the top bulged portions engage so as to be spaced from the associated side sheet; the space between said side sheets and bulged portions being filled with a suitable refractory material 25. The bottom bulged portions of said elements rest upon longitudinally spaced straps 26—26 fixed at their ends to the side portions of the mud ring and the space between the bottom bulged portions of said elements are bridged or closed by a brick arch 27 in which there is provided at a point between its ends, an air inlet opening 28 to support combustion.

The intake neck of each element is connected with the bottom of the boiler barrel by a conduit 29 and to facilitate assembly and to reduce cost of manufacture, I preferably make said conduit in more than one section. As best shown in Fig. 1 I make said conduit of 25 a substantially straight tubular section 30 which is fixed to the associated intake neck 23 and passes beneath the front portion of the mud ring and an elbow section 31 which is fixed at one end to the section 30 and curves 29 upwardly to be fixed to the barrel of the boiler at a point well in advance of the front water leg 12. Preferably said straight tubular and elbow sections are flanged as shown for attachment, the one to the other.

35 The rear end extension 22 of each top bulged portion is connected with the adjacent side leg 11 by a combined riser and elbow 32, one end of which is butt-welded to said extension as at 33 and the other end of which enters and is fixed to a flexible diaphragm portion 34 formed in the side sheet. The riser 32 is preferably short in height and is connected to the side sheet, at a point a suitable distance above the mud ring and toward 45 the rear water leg of the boiler.

The elements 18—18 are disposed in the mid portion of the firebox so that the front and rear ends of the elements are spaced from the like ends of the firebox. The space to 50 the front of said elements is closed by a front or burner wall 35 and the space to the rear of said elements is closed by a rear or flash wall 36, both walls being made of fire-brick. In the front or burner wall there is 55 located a fuel nozzle 37 of the oil burner type and said burner projects through an opening 38 in the burner wall 35.

In operation, the intense heat from the fuel 60 burning in suspension, in the firebox over the elements, causes a rapid absorption of heat by the upper sides thereof, which heat in turn is taken up by the water in said elements, thus converting part of it into steam. Because of the inclined positions of the elements, a 65 rapid flow of water from the conduits 29 into

the elements takes place and from there, passes through the risers into the side water legs of the boiler. By reasons of the connections described for each element, a large volume of water enters each element along its entire bottom side and as the discharge of each element is at one end and to the rear of each element, it is assured that the elements which present a large superficial area will at all times be filled with water to absorb the heat units from the fuel burning in suspension. As the discharge from each element is located near the rear and bottom end of each side water leg, the upward flow of water in the side legs will draw upon the water in the rear leg so that circulation is materially increased in both side and rear water legs.

70 The parts described are confined to firebox dimensions so that they do not interfere with the numerous other parts of the locomotive and they are so disposed in the firebox that they are not subjected to such widely different temperature changes as will cause them to be seriously affected by resulting strains and stresses.

75 As is apparent, the construction described, readily lends itself for complete removal when it is necessary under certain conditions to convert the firebox into a coal burner. While in describing the invention I 95 have referred in detail to the form, arrangement and construction of the various parts thereof, the same is to be considered merely as illustrative so that I do not wish to be limited thereto except as may be pointed out 100 in the appended claims.

90 I claim as my invention:—

1. A locomotive boiler construction embodying therein, a barrel and a firebox having sheets forming parts of the front, rear and side water legs of the boiler, a pair of relatively flat, hollow water heating and circulating elements disposed in the firebox and each extending downwardly and inwardly from an associated side sheet, means providing an intake for boiler water from the barrel of the boiler connected to the inner bottom side margins of said elements and other means providing a discharge for each element at the rear end of the top marginal side thereof, which opens into one of said legs adjacent another one of said legs.

105 2. A locomotive boiler construction embodying therein, a barrel and a firebox having sheets forming parts of the front, rear and side water legs of the boiler, a pair of relatively flat, hollow water heating and circulating elements disposed in the firebox and each extending downwardly and inwardly from an associated side sheet, a conduit providing 110 an intake for the inner bottom side margin of each element, for delivering boiler water thereto and means connecting the rear end 115 of the top marginal side of each element with 120

125 130

an associated side water leg, near said rear water leg.

3. A locomotive boiler construction embodying therein, a barrel and a firebox having sheets forming parts of the front, rear and side water legs of the boiler, a pair of relatively flat, hollow water heating and circulating elements disposed in the firebox and each extending downwardly and inwardly 5 from an associated side sheet, each element having bulged portions along each side margin, means providing an intake for each bottom bulged portion for delivering boiler water thereto and means connecting the rear end of 10 each top bulged portion with one of said water legs.

4. A locomotive boiler construction embodying therein, a barrel and a firebox having sheets forming parts of the front, rear 20 and side water legs of the boiler, a pair of relatively flat, hollow water heating and circulating elements disposed in the firebox and each extending downwardly and inwardly from an associated side sheet, each element 25 having bulged portions along its top and bottom side margins, means providing an intake for each bottom bulged portion for delivering boiler water thereto and a riser connected at one end to the rear end of each top bulged 30 portion and opening through an adjacent side sheet.

5. A locomotive boiler construction embodying therein, a barrel and a firebox having sheets forming parts of the front, rear 35 and side water legs of the boiler, a pair of relatively flat, hollow water heating and circulating elements disposed in the firebox and each extending downwardly and inwardly from an associated side sheet, each element 40 having bulged portions along its top and bottom side margins, means providing a conduit connecting the front end of each bottom bulged portion with the barrel at a point forward of the front water leg and a riser connected at one end to the rear end of each top 45 bulged portion and connected to and opening through an adjacent side sheet at a point above said top bulged portion.

In testimony whereof, I have hereunto set 50 my hand, this 31st day of May, 1928.

ARTHUR WM. NELSON.
